ROCKET LAUNCHING DEVICE

Aden B. Meinel, Berkeley, Calif., assignor to the
United States of America as represented by the
Secretary of War

Application January 20, 1947, Serial No. 723,159

7 Claims. (Cl. 89—1.7)

1

This invention relates to a new and useful improvement in rocket launchers and is designed more particularly to provide a closed breech launcher for use under conditions which prevent use of an open breech launcher, as in tank turrets. The closed breech launcher has certain recognized advantages over the open breech type, such as increased range, which would make its use desirable under conditions in which an open breech type could be used. While the character and functioning of the breech mechanism required for such closed breech launchers present many problems requiring satisfactory solution for efficient operation of the launcher, this invention is not relevant to such matters, as it concerns only the structure of the launcher tube, it being assumed that the improved tube is equipped with a satisfactory breech mechanism. Since the functioning of closed breech and open breech launchers are quite dissimilar, this invention is concerned with satisfactorily solving the problems involved in the operation of closed breech launchers.

Extensive investigation and experimental work have been carried on to overcome the detrimental effect of the gases of the propellant which in this type of launcher have no breech escape and must be evacuated from the launcher tube forwardly of the breech. The particularly novel and useful features of the improved tube of this invention are the channel rails on which the rocket moves through the tube, the muzzle-brake comprising gas discharge ports, and a gas obturating ring, and the peculiar relative proportions and relation of the novel elements, which produce a launcher tube which has successfully obviated the defects formerly inherent in such launchers. It has been found that satisfactory launching can be secured if the launching tube is designed to afford an area between the muzzle-brake and the muzzle through which the flow of the gases of the propellant are substantially eliminated so that there are no disturbing effects of the propellant gases trapped in the tube by the closed breech, when the rocket leaves the muzzle unaffected by any interfering action of gases escaping from the muzzle.

While there is disclosed in the drawing and hereinafter fully described one specific embodiment of the invention, it is to be distinctly understood that the invention is not considered to be limited to said specific embodiment but that its scope is defined by the claims appended hereto.

In the drawing:

Fig. 1 is a side elevation of the launcher.

2

Fig. 2 is a fragmentary, enlarged, vertical section of the tube of the launcher, the rocket in the tube shown in broken lines.

Fig. 3 is an enlarged, vertical section on the line 3—3 of Fig. 1, in the direction of the arrows.

Fig. 4 is an enlarged, vertical section on the line 4—4 of Fig. 1, in the direction of the arrows.

Fig. 5 is an enlarged, vertical section on the line 5—5 of Fig. 1, in the direction of the arrows.

10 As illustrated in the drawing, the launcher has a suitable breech casting 1, providing with recoil ways 2, and breech housing 3, for the breech block (not shown) and into which the tube 4, is threaded. The tube 4, is provided with three 15 guide rails 5, symmetrically disposed at intervals of 120° on the inner periphery of tube 4. Each rail 5 consists of a channel which is substantially U-shaped in cross-section and which is provided with lateral base flanges 6 and 7. The base flange 20 6 is attached to the inner face of tube 4 as by screws 8, or by welding. Plates 7 bear against the inner face of tube 4, unattached thereto, to permit slight movement of channels 5 radially of tube 4, channels 5 and flanges 6 and 7 being 25 sufficiently resilient. Rails 5 are somewhat spaced forwardly of the breech end of tube 4 and have oblique rear end faces 9, forming intake ports 10, for channels 5. Each channel 5 is closed 30 at the muzzle by a plug 5—a. Each channel 5 has an outlet port 11, opening through the wall of tube 4. Tube 4 is provided with outlet ports 12, two ports 12 being provided in each section 35 of the periphery of tube 4 between ports 11. Ports 11 and 12 are in the form of longitudinal slots through the wall of tube 4, forming a muzzle-brake for tube 4. These slots are of uniform length and slots 12 are substantially twice the width of slots 11. They are spaced from the 40 muzzle not less than one quarter of the length of tube 4, their forward and rear ends lying in common planes transverse to the axis of tube 4, respectively.

The tube 4 is provided with an obturating ring 45 13, disposed forwardly of the ports 11 and 12. This ring 13 comprises three arcuate members 14 fitted between the rails 5. Each portion 14 has a recess 14' in which is slidable the flange 7 of one of rails 5. The rear end 15 of the ring 13 is spaced somewhat rearwardly of the forward ends of the ports 11 and 12. See Figure 1. The ring 13 has a frusto-conical portion 16 divergent from end 15 to the forward ends of ports 11 and 12. The front end 17 of ring 13 is substantially midway between the forward ends of ports 55

11 and 12 and the muzzle of tube 4. The forward portion 18 of ring 13 diverges at an acute angle to the inner surface of tube 4.

The above described elements of the launcher are so designed and related that when the rocket R is introduced into the tube 4 through its opened breech, the bourrelets B and B-1 of rocket R are received on rails 5, which resiliently bear thereon, thereby coinciding the axes of the rocket R and tube 4. It will be noted that the dimensions of the elements of the launcher are such that in its passage through tube 4, the rocket R is supported on rails 5 in such a manner that the rear bourrelet B passes forwardly of the ports 11 and 12 before the forward bourrelet B-1 leaves rails 5 at the muzzle.

The specific embodiment of the invention illustrated in the drawing and hereinbefore fully described is designed for launching a 3.5" rocket. Successful tests of this launcher have indicated that the correct dimensions are as follows. The tube 4 should measure fifty inches from the breech to the muzzle. The ports 11 and 12 should be three inches long, and their rear ends should be not less than fourteen and one-half inches rearwardly of the muzzle. The obturating ring 13 should be six inches long, its frusto-conical portion 16 extending into the ports 11 and 12 being one half an inch long, and its divergent forward portion 18 being two inches long. The foregoing dimensions provide an area, not less than twelve inches long, in the tube 4 between the rear end of the obturating ring 13 and the muzzle.

It is obvious from the foregoing description of the details of construction of the improved launcher that when the propellant of the rocket R is ignited the gases trapped in tube 4 by its closed breech pass forwardly through tube 4 between rails 5. Because of the pressure of the gases, due to the closed breech, this gas flow is at a rate superior to the rate of travel of rocket R. The gases, therefore, flow in the spaces 19 between the inner surface S of tube 4 and the wall W of the rocket R (Fig. 3). The gases preceding the rocket R escape from tube 4 at the muzzle. Since these gases are ahead of rocket R, their discharge from the muzzle does not affect the rocket R travelling on rails 5. When the forward end of rocket R reaches the rear end of ring 13, a throttling action is produced by sections 14, causing the major portion of the gases posterior to rocket R to be evacuated through discharge ports 12, the portion 16 of ring 13 assisting the discharge.

The trapped gases also enter channels 5 through intake ports 10 and are evacuated therefrom through discharge ports 11, the forward ends of channels 5 being sealed by plugs 5-a. Thus the portion of the tube 4 forwardly of the rear end of ring 13, when rocket R reaches the rear end of ring 13, receives only the negligible amount of the unevacuated gases flowing forwardly in the spaces 20 between the inner surfaces S-1 of members 14 and the outer wall W of the rocket R (Fig. 4). Due to the divergence of portion 18 of ring 13, this amount of the gases is considerably expanded forwardly of ring 13 reducing the pressure sufficiently to render the unevacuated gases innocuous when discharged from the muzzle.

Having described the invention, what I claim is:

1. In a rocket launcher, the combination of a launching tube closed at its breech and hollow guide rail means in said tube for coinciding the

longitudinal axes of the tube and a rocket launched therefrom during the period of travel of the rocket through the tube, said rails constituting conduit means for discharging propellant gases of the rocket from the breech end of the tube forwardly along said tube.

2. In a rocket launcher, the combination of a tube closed at its breech end, and a plurality of hollow, circumferentially-spaced rocket-guiding rails mounted on the inner surface of said tube and extending longitudinally therealong, at least one of said rails comprising a gas conduit having an intake port within said tube adjacent the breech end thereof, there being a discharge port opening through the wall of said tube intermediate the ends thereof, and communicating with the interior of said one rail.

3. In a rocket launcher, the combination of a tube having its breech end gas tight, more than two, uniformly circumferentially spaced rocket-guiding rails mounted on the inner surface of the tube and extending longitudinally therealong; an obturating ring comprising a plurality of arcuate circumferentially extending members mounted on the inner surface of the tube between said rails there being a slot through the wall of said tube immediately rearwardly of said ring.

4. In a rocket launcher, the combination of a tube having a closed breech and a slot comprising a muzzle-brake, said slot being located approximately one-quarter of the length of said tube from its muzzle end, a plurality of rocket-guiding rails mounted on the inner surface of the tube, each of said rails comprising a gas conduit having an intake port adjacent the breech end of said tube, and a discharge port through the wall of said tube and in the same transverse plane as said slot, and an obturating ring comprising a plurality of arcuate members mounted on the inner surface of the tube between the rails, the rearward end of said ring lying in said plane.

5. In a rocket launcher, the combination of a tube having a closed breech; a plurality of circumferentially spaced resilient rocket-guiding rails extending longitudinally of said tube, each of said rails being substantially U-shaped in cross section and provided with lateral outwardly extending flanges, one said flange being fixed to the inner face of said tube, and the other being in slidably contact thereon; and an obturating ring comprising a plurality of arcuate members mounted on the inner surface of the tube between the rails there being at least one slot through the wall of said tube immediately rearwardly of said ring.

6. In a rocket launcher, the combination of a tube having a closed breech, a plurality of rocket-guiding rails mounted on the inner surface of said tube, each rail comprising a gas duct having an inlet port communicating with the interior of said tube adjacent its breech end, there being slots through the wall of said tube, said slots being located approximately one-fourth the length of said tube from the muzzle end thereof, each slot communicating with the interior of a respective rail to form a gas discharge port, there also being slots through the wall of said tube between said rails, substantially in the same transverse plane with said first-named slots, and obturating ring means in said tube just forwardly of said slots.

7. In a rocket launcher, the combination of a tube having a closed breech and a plurality of hollow rails circumferentially spaced about the

inner surface of said tube to engage and guide a rocket for translation therealong, the ends of said rails adjacent the breech of said tube being open, there being a port through the wall of said tube to the interior of each rail, there being additional ports through the wall of said tube to the interior thereof, all said ports being approximately one-fourth the length of said tube from the muzzle thereof, and obturating ring means in said tube just forwardly of said ports, said ring means comprising arcuate sections secured to said tube wall between said rails and forming a gas tight fit with a rocket guided on said rails.
